(57) **CLAIM**

The ornamental design for a toy as shown and described.

DESCRIPTION

FIG. 1 is a perspective view of a first part of the toy showing my new design, shown separately for ease and clarity of illustration;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a perspective view of a second part of the toy showing my new design, shown separately for ease and clarity of illustration;

FIG. 10 is another perspective view thereof;

FIG. 11 is a front view thereof;

FIG. 12 is a back view thereof;

FIG. 13 is a left view thereof;

FIG. 14 is a right view thereof;

FIG. 15 is a top plan view thereof;

FIG. 16 is a bottom plan view thereof;

FIG. 17 is a perspective view of a third part of the toy showing my new design, shown separately for ease and clarity of illustration;

FIG. 18 is another perspective view thereof;

FIG. 19 is a front view thereof;

FIG. 20 is a back view thereof;

FIG. 21 is a left view thereof;

FIG. 22 is a right view thereof;

FIG. 23 is a top plan view thereof;

FIG. 24 is a bottom plan view thereof;

FIG. 25 is a perspective view of a fourth part of the toy showing my new design, shown separately for ease and clarity of illustration;

FIG. 26 is another perspective view thereof;

FIG. 27 is a front view thereof;

FIG. 28 is a back view thereof;

FIG. 29 is a left view thereof;

FIG. 30 is a right view thereof;

FIG. 31 is a top plan view thereof;

FIG. 32 is a bottom plan view thereof;

FIG. 33 is a perspective view of a fifth part of the toy showing my new design, shown separately for ease and clarity of illustration;

FIG. 34 is another perspective view thereof;

FIG. 35 is a front view thereof;

FIG. 36 is a back view thereof;

FIG. 37 is a left view thereof;

(Continued)

FIG. 38 is a right view thereof;
FIG. 39 is a top plan view thereof;
FIG. 40 is a bottom plan view thereof;
FIG. 41 is a perspective view of a sixth part of the toy showing my new design, shown separately for ease and clarity of illustration;
FIG. 42 is another perspective view thereof;
FIG. 43 is a front view thereof;
FIG. 44 is a back view thereof;
FIG. 45 is a left view thereof;
FIG. 46 is a right view thereof;
FIG. 47 is a top plan view thereof;
FIG. 48 is a bottom plan view thereof; and,
FIG. 49 is a perspective view of a Toy showing my new design, in a combined state.
